FUSED CUTOUT

David C. Hubbard, Centralia, Mo., assignor to
 A. B. Chance Company, Centralia, Mo., a corporation of Missouri

Application April 14, 1941, Serial No. 388,501

18 Claims. (Cl. 200—114)

The present invention relates to fused cut-outs and is particularly concerned with fused cut-outs of the type adapted to be enclosed and utilized on high tension transmission circuits. For example, the device illustrated is proportioned and designed for 50 amperes at 5,000 volts, and it is to be understood that devices embodying my invention may be constructed for use at various voltages and for breaking various currents by variations in the size, spacing, etc. of its component parts, which will be evident to one skilled in the art, from the following description of the invention.

One of the objects of the invention is the provision of an enclosed fused disconnect of such a construction that the housing remains closed during and after operation, so that it is adapted to protect the interior mechanism from the action of the elements, such as rain, sleet, snow, ice, etc.

Another object of the invention is the provision of a fused disconnect in which the dangling fuse leader, which appears after the circuit has been broken by the fuse, is not energized, thus eliminating the hazard which is presented by an energized leader, such as is present in the devices of the prior art.

Another object of the invention is the provision of an improved fused disconnect in which the fuse mechanism provides a double break in the circuit, thereby aiding in snuffing the arc, one break occurring within the fuse tube, at the ruptured fuse element, and another break occurring at the point of contact of the fuse unit with a contact carried by the housing.

Another object of the invention is the provision of an improved fused disconnect in which the clip for supporting the fuse unit carries no current, so that the resiliency of the spring clip is not affected by the passage of current, and the device may be used for a long period of time without bad effects on the resiliency of the spring clip.

Another object of the invention is the provision of an improved fused disconnect in which the electrical connecting contacts of the brush type are provided, and in which these contacts are provided with current carrying pigtails or leads so that the contacts will not be affected by the passage of current and so that they will retain their resiliency for a long period of time. This also eliminates the possibility of the sticking of the fuse assembly because of burned or corroded clip contacts.

Another object is the provision of an improved fuse disconnect assembly in which the

fuse assembly may be removed by a disconnect stick, thus eliminating the necessity for the operator to approach line parts with his hand for removing or replacing this unit.

- 5 Another object of the invention is the provision of an improved disconnect which effects a triple contact break on manual operation, thereby tending to reduce the intensity and length of arc formed when the circuit is broken.
- 10 It is a further object of the invention to provide for the breaking of the circuit first at the top contacts of the assembly so that the tendency for the formation of an arc at the bottom contact is thus eliminated or reduced. As an arc has the tendency of traveling upward and spreading to other parts, this breaking of the circuit at the top, first, reduces or substantially eliminates the possibility of damage by the formation of an arc below, which might travel upward.
- 15
- 20 Another object of the invention is the provision of an improved housing structure by means of which the breakage of the porcelain boxes at the hinge points may be eliminated, or at least the construction may be such that if the box breaks, the cover may be held by the improved reinforcing devices provided according to the invention.

Another object of the invention is the provision of an improved housing construction so that if the door is broken in two, the contacts at the top will swing out, opening the circuit through a double contact break, but the fuse assembly will not be dislodged.

Another object is the provision of an improved structure for securing contacts, clips, latches, etc. of a metallic nature to a porcelain or glass housing member with a minimum amount of labor in the construction of securing devices.

Other objects and advantages of the invention will be apparent from the following description and the accompanying drawings, in which similar characters of reference indicate similar parts throughout the several views.

Referring to the four sheets of drawings accompanying the specification,

Fig. 1 is a side elevational view of an enclosed fuse disconnect switch constructed according to the invention, shown in connection with one preferred mode of support;

Fig. 2 is a transverse sectional view, taken on the plane of the line 2—2 of Fig. 1, looking in the direction of the arrows;

Fig. 3 is a front elevational view of the disconnect assembly with the cover removed;

Fig. 4 is a sectional view taken through the de-

vice of Fig. 1, on the plane of the line 4—4 of Fig. 1, looking in the direction of the arrows;

Fig. 5 is a vertical sectional view, taken on the plane of the line 5—5 of Fig. 3, with the cover on the box and the parts in the closed circuit position;

Fig. 6 is a view similar to Fig. 5, with the parts in the open circuit position, the fuse having been ruptured;

Fig. 7 is a fragmentary sectional view through the fuse assembly;

Fig. 8 is a sectional view, taken on the plane of the line 8—8 of Fig. 6;

Fig. 9 is a sectional view, taken on the plane of the line 9—9 of Fig. 6;

Fig. 10 is a fragmentary sectional view similar to the lower end of Fig. 5, with the target in the position which it assumes when it is forced downward by the spring 133 on rupture of the fuse;

Fig. 11 is a bottom end view of the fuse assembly;

Fig. 12 is an inside view of the cover, taken on the plane of the line 12—12 of Fig. 5;

Fig. 13 is a fragmentary sectional view, showing the preferred mode of securing the supporting bolts for the housing in the body of the housing;

Fig. 14 is a fragmentary sectional view of the structure of an improved mode of support of the spring clips and contacts on the housing or cover of ceramic materials;

Fig. 15 is a plan view of the securing device of Fig. 4, with the spring clip removed, showing the details of its structure.

Referring to Fig. 1, the fused disconnect is there indicated in its entirety by the numeral 10, and it preferably comprises an insulating housing, such as a housing of porcelain or the like, which is provided with a pair of rearwardly extending threaded metal studs 11, 12 located on and projecting from the rear side 13 of the housing.

The studs 11 may be used with strap metal bracket members 14, 15 for securing the assembly to a cross arm 16. Each of these bracket members 14, 15 comprises a metal strap having a pair of flanges 17 at right angles to each other, the length of these flanges being equal to the height and width of the cross arm.

Each of these brackets 14, 15 also has a pair of diagonally extending attaching flanges 18, 19 at two diagonally opposite corners of the cross arm 16, and the attaching flanges are provided with apertures for receiving the screw bolts 20, having nuts 21, whereby the brackets are clamped on the cross arm 16.

The bracket 14 preferably has its attaching flange 18 provided with an extension and with the supporting flange 22 extending upward at an acute angle, and provided with apertures for receiving the studs 11, 12. The nuts 23 clamp the flange 22 of bracket 14 against the housing 13, the studs having their heads embedded in the porcelain, and lock nuts 24 may be employed to assure the fixity of the nuts 23.

I desire it to be understood that any of the various types of supporting brackets may be used, although the one illustrated is one of the preferred forms, as it supports the housing in such position that the cover will remain open, when opened to a predetermined point.

The housing of the fused disconnect 10 preferably consists of two parts, the main housing member 25 (Fig. 1) and the cover 26. The main housing member preferably is of substantially box shape, having a relatively thick rear wall 27

and a pair of thinner forwardly extending walls 28, 29 at each side.

The front of the main housing member 25 is open so that it may be closed by the cover 26, which is adapted to be received between parts of the side walls 28, 29 and rear wall 27 define a fuse unit chamber 30, the upper end of which is closed by the upper wall 31 (Fig. 5), and the lower end of which is partially closed by a lower wall 32, all of these walls being integral with the main housing member 25.

The lower wall 32 is cut away at 33 to permit the passage of a target 34 carried by the fuse assembly, which is indicated in its entirety by the numeral 35. This lower wall is also cut away to provide an opening at 36 (Fig. 3 and Fig. 6) immediately below the lower end of the tube of the fuse assembly 35, which encloses the fuse.

Thus the lower end of the housing is open at all times for projection of the target 34, which indicates that the fuse is ruptured, and to permit the fuse, which is blown out of the tube 37 to dangle downward out of the housing, where it is blown by the force of gases produced by the rupture of the circuit and fusing of the fuse in the tube 37.

The side walls 28, 29 are preferably rabbeted as at 40, thus providing a shoulder 41 (Fig. 4) for engagement with the cover 26, and laterally projecting flanges 42 project beyond each side of the cover 26. This provides a more effective closure for the fuse assembly against the action of the elements.

At the upper end of the housing the side walls 28, 29 are provided with ears or extensions 43, serving as a support or hinge for the cover 26, by means of a pintle 44. These hinge ears 43 have been subject to breakage, and the side walls of the housing are preferably provided with grooves 45 of rectangular cross section for receiving a reinforcing galvanized iron strap 46 of substantially U shape, which fits in the grooves 45 on each side of the housing, and in a similar groove 47 on the face 13 of the housing, and the strap 46 has its legs extending to and supporting the pintle 44.

The strap legs 46 and ears 43 have apertures for receiving the pintle 44, which preferably consists of a cylindrical metal member having a head at one end, and its other end riveted over, as shown in Fig. 2. The pintle 44 extends through a cylindrical bore 48, which is located in and traverses the cover 26.

The upper wall 31 preferably does not extend outward as far as the ears 43, terminating at curved edge 49 (Fig. 5), which serves as a stop member for supporting the cover in open position, as indicated in dotted lines in Fig. 6.

The housing is also rabbeted inside the two ears 43, the shoulder 41 (Fig. 3) extending the full length of the side walls 28, 29 and across the rear wall at 50, inside the fuse assembly chamber 30.

The rear wall 27 of the main housing member 10 is preferably not of uniform thickness, but is provided with portions of different thickness, dividing the chamber up into a number of different parts, and providing support for a number of different switch elements, as follows:

At the upper end of the chamber the rear wall is provided with a flat shelf at 51, providing a support for the fuse assembly hinge, indicated in its entirety by the numeral 52. The fuse assembly hinge consists of a metal member, having a flat attaching flange 53, and a pair of

downwardly and outwardly extending bearing flanges 54, located at right angles to the attachment flange 53.

The attachment flange 53 is secured in place by a pair of screw bolts 55, passing through apertures in the attachment flange 53, and threaded into nuts or equivalent threaded members 56, embedded in the porcelain body of the rear wall 27. The bearing flanges 54 extend outward and downward, and are each provided with the inwardly extending and downwardly curved slots 57, the trunnions 58 carried by the fuse assembly 35.

The lower part of the bearing flanges 54 take the form of a hook 59 so that the trunnions 58 may be inserted by an upward and lateral movement and brought to rest on the hooks 59 by dropping the fuse assembly into place.

The flanges 54 are spaced from each other by a distance equal to the lateral thickness of the fuse assembly at its upper end. The member 52 acts as a pivotal support for the fuse assembly, but is insulated. Its parts carry no current, and thus there is no possibility of the fusing of the pivotally mounted parts 58 and 54.

The fuse assembly chamber 30 is preferably deepest at the surface 60 (Fig. 5), which flat surface serves as a support for a contact and connector arm, indicated in its entirety by the numeral 61. This contact and connector arm 61 comprises a member made of conducting metal, such as copper, having a body portion 62 of substantially rectangular cross section, and preferably provided with a through bore 63 extending axially through the body portion 62.

A pair of threaded bores 64 extends from the outer surface 65 of the body portion 62 into communication with the bore 63, and these threaded bores serve to receive the screw bolts 66, which are adapted to extend into the bore 63 and clamp a conductor in this bore.

The body portion 62 of this connector is preferably formed with an anchoring formation 67, which may extend into the porcelain rear wall 27, and may be anchored therein to hold the connector in its proper position.

The anchor 67 may be of dove-tailed or other desirable shape, and is preferably of substantial length, to assure the anchoring of the connector in the housing. The side walls 28, 29 are preferably formed with the cylindrical through bores 68 registering with the bore 63 in the connector 61 at each end, and the bores 68 in the housing walls are of larger size, adapted to receive not only the conductor, but its insulating covering, the end of the insulating cover being brought into abutting relation with the flat end of the connector body 62.

As bores are provided in the side walls at each side, and the bore in the connector is a through bore, the connections may be made from either side of the housing, the screw bolts 66 being brought into clamping relation with the conductor in the bore 63.

The housing walls 28, 29 are provided on their outer faces surrounding the through bores 68 and similar bores 69 within outwardly projecting rib 70 of substantially U shape in elevation, as shown in Fig. 1, the ribs being preferably curved and substantially half cylindrical in cross section.

These curved ribs have their legs extending downwardly, and serve to facilitate drainage of water from the face of the housing and to prevent in some measure the access of water to the 75 88.

interior of the housing, by reason of such drainage.

The connector body 62 is provided at one end (the left in Fig. 3) with an outwardly projecting contact arm 71, which may extend at right angles to the main body 62, and may be substantially rectangular in cross section. At its outer end it is preferably provided with a head 72, which may be rectangular in shape, and which 10 may provide a larger plane contact area 73 on its outer face.

The face 73 is located substantially on the same plane as the outer edge of the ribs 42 of the housing (Fig. 4), and the arm 71 is located slightly 15 inwardly of the side wall 28 in the chamber 30, for engagement with a contact, further to be described.

In order to separate the upper contacts of the assembly from the lower contacts, the main housing member 25 is preferably provided with a partition 74 (Fig. 3, Fig. 5) located below the connector 61, and slightly higher than midway between the ends of the housing.

This partition 74 has its outer edge 75 flush 25 with the rabbeted shoulders 41 and 50 of the main housing member, and the partition 74 is tapered in thickness toward the outer edge for convenience in molding. In the same way the housing walls 28, 29 may taper in thickness toward their outer edges, and the chamber 30 may be narrower toward its bottom for convenience in withdrawal of the mold parts.

The partition 74 is preferably provided with a U-shaped groove 76, the walls of which are 35 slightly spaced from the insulating tube 37 of the fuse assembly 35, so as to permit the fuse assembly to be placed in the chamber 30 in position traversing the partition 74.

The rear housing wall 27 is provided adjacent 40 its lower end, but spaced therefrom, with another shelf 77 adapted to provide a support for a spring clip 78, which engages the tube 37 of the fuse assembly 35 and holds it in closed circuit position.

The spring clip 78 (Fig. 6) has a flat attaching 45 flange 79, through which a pair of screw bolts 80 pass, and the screw bolts are threaded into nuts or equivalent threaded members 81, embedded in the porcelain body 82. The attaching flange 79 of the spring clip 78 supports a pair of spring 50 flanges 83 of identical shape, but oppositely disposed. These spring flanges each have a diagonally outwardly extending straight portion 84 and a curved tube-engaging portion 85, which is 55 partially cylindrical. At their outer edges the spring flanges 83 are provided with outwardly curved lips 86, spaced sufficiently so that when these lips come into engagement with a tube of the size of the tube 37 of the fuse assembly the spring flanges 83 are cammed apart.

Further pressure on the tube 37 into the spring 60 flanges 83 causes the tube to come to rest in the position of Fig. 4, where its opposite sides are engaged by the cylindrical portions 85 of the spring flanges 83. It should be noted that this 65 spring clip engages only the insulating tube 37 and holds the fuse assembly in place, but it does not carry any current, and there is no possibility of the spring clip parts becoming fused or of the switch parts sticking due to fusing of the 70 clip.

At its lower end the fuse assembly chamber 30 is again provided with a deeper portion at the flat surface 87 on the inside of the rear wall 27 for the purpose of supporting another connector 75 88.

This connector comprises a body portion of substantially similar shape to the body 62 of the connector 61, and it likewise has the through bore 63 for receiving the conductor, the through bore being in registry with the apertures 69 in the side walls.

This connector is likewise provided with the clamping screw bolts 66, and it is likewise anchored to the porcelain body 25. At its left end this connector body 88 has an outwardly extending integral lug 89, the right face of which serves as a flat shoulder engaging at the edge of a spring contact 90, which may thus be secured in place against rotation by a single screw bolt 66 passing through the contact 90 and threaded into the connector body 88 (Fig. 6).

This contact member comprises a strip of resilient electrically conducting metal, such as spring bronze of adequate thickness to assure its having a certain degree of stiffness, and it may be curved backwardly at 92 and outwardly again at 93 and backwardly at its tip 94.

Its curved face at 93 serves as the contacting portion of the contact, and its end is connected by solder to one end of a braided copper pigtail or lead 95, the other end of which is provided with an aperture for receiving the screw bolt 66 so that it may be clamped between the connector body 88 and the contact member 90.

The braided copper wire pigtail 95 being soldered to the rear side of the contact 91 at its end, and being in good electrical connection with the connector 88, the spring contact 90 does not need to carry anything but a negligible amount of current, most of the current going through the pigtail. Thus its resilient characteristics will not be impaired, even though it is used for a long period of time at its rated current.

The spring contact 90 projects downward into the groove 33, from which the target projects. This contact is adapted to engage a contact carried by the target and fuse assembly further to be described.

The fuse assembly or fuse unit, indicated in its entirety by the numeral 35, is removable as a unit from the chamber 30, and it is adapted to be handled by means of an ordinary disconnect or fuse stick. For this purpose its upper metal fitting 100 (Fig. 6) may comprise a cast metal member of substantially cylindrical shape at its lower end, except that it is provided with a plane surface 101 on its face.

It also has above this face an integral forwardly projecting arm 102 with a pair of downwardly extending prongs 103, 104 (Fig. 3). These prongs 103, 104 are spaced from each other by the upwardly extending groove 105, which is bounded by the two parallel edges of the prongs 103, 104 and by a circular upper portion at 106.

The spacing between the prongs 103, 104 and the plane face 101 is sufficient to receive the relatively flat circular head of the fitting at the end of a fuse puller, and the width of the groove 105 is sufficient to receive the shank of this fitting on the end of a fuse puller so that the fuse assembly 35 may be lifted and handled very conveniently by means of an ordinary fuse puller.

The lower surface 107 of the forwardly projecting arm 102 is also substantially plane, although this may be of no importance where a round headed fuse puller is employed.

The metal fitting 100 is provided with an axially extending bore 108 extending into its 75

lower end and adapted to have a tight frictional engagement with the cylindrical outer surface of the insulating fiber tube 37.

It also has an inwardly extending annular flange 109 at the end of the bore 108, the flange 109 defining a smaller bore 110 through which the fuse passes.

At its upper end the fitting 100 has a threaded counterbore 111, and the flange 109 has an upper plane surface 112. The threaded counterbore 111 is adapted to receive a closure plug 113, having a threaded portion 114 and a head provided with an overhanging annular ledge 115 that overhangs the plane annular end surface 116 of the fitting 100.

The closure plug 113 has a flat lower end 117 adapted to engage the flat top of the button 118 of the fuse, which has a cylindrical portion 119 in the aperture 110.

Any type of commercial fuse having such a button and a fusible portion, and a flexible pigtail, may be used in this fuse assembly, the one illustrated being constructed as follows.

The fuse head is preferably of relatively harder material and is provided with a flat ribbon-like shank 120 extending downward from the cylindrical portion 119. This shank has a circular groove at 121 providing a portion of reduced cross section at this point.

30 The ribbon shank 120 is secured by soldering or brazing to a fuse wire 123 at 122, the lower end of which is secured in a copper tube 124 by soldering, the copper tube being secured by a sheet metal clip 125 and by soldering to the flexible stranded conductor or pigtail 126.

An annular collar 125' on the copper tube 124 engages one end of an insulating fiber tube 126', which is confined between the collar 125' and the end of the ribbon shank 120, housing the melt-40 able portion of the fuse.

When located in the fuse assembly, this fuse has its button 118 resting on the annular shoulder 112 and clamped against it by the closure plug 113. The main part of the fuse extends downward into the fiber tubing 37, and the pigtail projects from the lower bent end of the fiber tube 37, where it is secured in a manner further to be described.

The upper end of the fitting 100 of the fuse assembly (Fig. 6) is provided with a pair of oppositely located trunnions 58 (Fig. 6) of cylindrical shape and adapted to be received in the slot 57 on the hook 59 of the upper supporting fixture 52 of the housing 10.

55 These trunnions 58 support the fuse assembly for pivotal movement on the common axis of the two trunnions, but they permit the removal of the fuse assembly by a lifting and outward pulling movement which is applied by means of a fuse puller having its head behind the prongs 103, 104 (Fig. 3). Two usual positions for the fuse assembly are shown in Fig. 5, where the fuse assembly is secured with the cover closed, and in Fig. 6, where the fuse assembly hangs loosely after the cover has been opened, the fuse having been ruptured.

The insulating tube 37 comprises a tube of indurated fiber or other suitable insulating material, the fiber being impregnated with an insulating compound, such as a phenolic condensation compound, dissolved in suitable solvents. It is of sufficient length to house the fuse and part of the fuse pigtail 126 so that the fuse pigtail extends from the lower end of the tube, as shown in Fig. 3.

Adjacent its lower open end, but slightly spaced therefrom, the insulating tube 37 supports another metal fixture, indicated by the numeral 127.

This metal fixture comprises a cast metal member, oval in plan, and formed with a pair of parallel axially extending bores 128, 129. The bore 128 has a tight frictional fit on the insulating tube 37, and the bore 129 terminates in an annular shoulder at 130, and has a similar fit on another similar insulating tube 131. The insulating tube 131 is adapted to house the plunger 132, which is spring pressed downward by the compression spring 133 (Fig. 6) to place a tension on the fuse.

The insulating tube 131 is also of indurated and impregnated fiber, but, as it is not used to house the fuse, it may be provided with a thinner wall, as shown in Fig. 6. It is of suitable length to house a fairly long compression spring 133, and the plunger 132, and, as shown, it extends upward slightly more than half way the length of the fuse tube 37. At its upper end the insulating tube 131 is closed with an insulating plug 134, secured in place by a transverse metal pin 135, passing through the plug tube, and riveted over at each end.

The plunger 132 (Fig. 6) comprises a cast metal member, having its main portion 136 of cylindrical shape, but provided with a laterally projecting flange 137 of substantially rectangular cross section.

At its lower end the plunger 132 is provided with an enlargement serving as a target 34 and also as a contact. This enlargement comprises a larger cylindrical body portion 138 integral with the cylindrical shank 136. The body portion 138 supports a laterally projecting arm 139 of rectangular cross section, terminating in a contact head 140, which is wider, in order to provide the flat contact face 141 of greater area.

The target 34 also has a laterally and downwardly extending integral arm 142 (Fig. 3), the end of which is provided with a head 143, having a partially circular groove 144 for engaging the fuse pigtail 126. The target 34 also has a threaded bore 145 for receiving the screw bolt 146, and the bolt 146 carries a special washer 147, having a tangentially projecting arm 148, which is turned upward at 149 to engage the arm 139, preventing rotation of the washer.

All of the parts of the target 34, including the screw 146 and the washer 147, are of metal of high electrical conductivity, as it forms a part of the electrical circuit.

At its upper end the plunger 132 is provided with a substantially cylindrical head 150, which may be secured on the plunger by means of a threaded bore 151, engaging a reduced threaded portion 152 and an annular shoulder 153 on the plunger 132.

A screw driver slot 154 is provided in the upper end of the head, in order that it may be driven home on the threaded portion 152. The spring 133 is compressed between the closure plug 134 and the head 150 of the plunger 132, urging the plunger 132 and the target 34 downward.

The side of target 34 may be painted red or some other distinguishing color, so that it may be more conveniently observed when it projects from the housing.

The fitting 127 is also provided on its front side, near its lower edge, with an integral downwardly projecting hook or shoulder member 155, having the flat shoulder 156 on its inner side.

This flat shoulder 156 is adapted to engage the inside surface of a keeper 157, carried by the cover 26 (Fig. 5), when the cover and fuse assembly are in the closed position of Fig. 5.

The arrangement of the pivotal supports of the fuse assembly 35 and the cover 26 on the housing 10 are such that the shoulder 156 and keeper 157 slide out of engagement with each other as they come to the position of Fig. 6 from that of Fig. 5. Therefore, the length of the shoulder 156 bears a definite relation to the lengths of the cover and fuse assembly and to the points of pivot of these latter.

The fuse assembly is adapted to be held in its closed position, that is, the position of Figs. 3, 4 or 5, by the engagement of the spring clip 18 with the sides of the tube 37, as shown in Fig. 4. This spring clip carries no current and engages the insulating tube and holds it in the housing, from which it may, however, be pulled by means of the cover 26, keeper 157 engaging behind the hook 155.

As the spring clip 18 carries no current, its resiliency will not be affected by any kind of use to which it is subjected, and it will operate for a long period of time without necessity for repair or replacement.

When the fuse assembly is in this position, the contact head 140 of the target 34 engages the contact 90, as shown in Fig. 5; but when the fuse is ruptured, the target moves downward to the position of Fig. 10.

Referring to Fig. 3, the mode of installation of a fuse will be apparent to one skilled in the art, from the arrangement of the parts illustrated therein. The pigtail 126 of the fuse passes out of the lower end of the tube 37. The plunger 132, having been forced upward to the position of Fig. 3 by hand, the pigtail 126 is located in the groove 144 of the target arm 142 and brought over on the arm 142, where it is further guided by a downwardly extending flange 158 (see Fig. 11). From there the fuse pigtail 126 passes under the washer 147 and is confined between the shank of the bolt 146 and the upwardly projecting arm 149 of the washer.

The pigtail may be given more than a full turn about the screw bolt 146 until its loose end emerges from beneath the washer 147 on the other side of the upwardly projecting lug 149. The screw 146 then being driven home, it will clamp the washer against the pigtail and assure the firm securing of the pigtail of the fuse to the target, with a good electrical contact.

The cover 26 may also comprise an integral porcelain member of substantially rectangular shape in plan and fitting in between the ribs 28 on the main housing against the rabbeted shoulders 41 and 50. For this purpose the cover may be formed with a pair of inwardly projecting ribs 160 (Fig. 4) which engage the shoulders 41, the inside of the cover being relieved at 161 between the ribs to make it slightly hollow and provide more space in the fuse assembly chamber 30.

The cover is preferably made thicker at its upper end portion. The middle section of the cover is shown in Fig. 4, and here it is preferably provided with a vertically extending outer reinforcing rib 162, which extends downward and is widened at its lower end (Fig. 5) to provide sufficient stock for the transverse aperture 163 (Fig. 5). This aperture is of sufficient size to receive the head of a fuse stick so that the head of the fuse stick or the hook of some other hot

line stick may be inserted in the aperture 163 to pull the cover open.

At its lower end, adjacent the lower fuse assembly fixture 127, the cover is formed with a larger recess 164, providing space for this fixture and for the latch 155 and keeper 157. The recess 164 is closed by a lower end wall 165 (Fig. 6), which, however, is provided with an inwardly extending groove 166 (Fig. 6) between the side ribs 160.

The base of this groove, that is, the flat surface 167, engages the flat flange 168 of the keeper 157. This keeper may consist of a strap of sheet metal, having a U-shaped portion 169 that is provided for the purpose of increasing the resiliency of the keeper.

The lower side of this U-shaped portion engages the flat inner surface of the wall 165, and this leg carries the flange 168, which engages the surface 167.

With this arrangement a single screw bolt 170, passing through the yoke of the U-shaped portion of the keeper 157, may be threaded into a threaded member 171 embedded in the porcelain to secure the keeper to the cover, without any possibility of rotation.

The other leg 169 of the U-shaped portion of the keeper 157 has the upwardly extending flange 172, which engages the shoulder 156 on the fuse assembly (Fig. 5).

At its upper end the cover 26 is preferably made thicker so that it may have a recessed portion 173 (Fig. 5) of sufficient depth to house the forwardly projecting prongs 103, 104 on the fuse assembly, and also for the purpose of providing space for a pair of contact members 174, 175 (Fig. 12).

These contact members are identical in shape, and are both carried by a conducting metal bridge 176, consisting of a rectangular bar of metal, having a pair of apertures 177. The apertures 177 are counterbored so that the heads of the screws 178 are depressed, and screws 178 pass through the aperture 177 and are threaded into threaded nuts 179 or other equivalent, embedded in the porcelain of the cover.

Thus the bridge 176 is fixedly secured to the cover and it extends from inside of one rib 160 to the inside of the other rib.

In the commercial embodiment of the invention I propose to make a bridge 176 and contacts 174, 175 all of one piece, in which case the pigtail 181 would be secured to the contacts by means of a screw and washer, instead of being clamped between the bridge and contact.

At each end the bridge 176 is rabbeted at 180 to provide space for attachment of a pigtail 181, and one of the contacts 175 or 174.

A screw bolt 182 passes through each contact 175 or 174, and through the braided pigtail 181, and is threaded into the bridge bar 176, clamping that end of the pigtail against the bridge bar. The other end of the pigtail 181 is soldered or brazed to the rear side of the contact.

The edge of each contact 174 or 175 engages the rabbeted shoulder at 180 so that only one screw 182 is necessary to secure the contact and pigtail to the bridge bar against rotation.

The major portion of the current is carried by the pigtail 181, thereby preventing the generation of heat in the contact, which would destroy its resiliency. The shape of the two contacts 174, 175 may be substantially the same as the contact 91, previously described.

The contact 174 is located to engage the fixed contact head 73 carried by the housing. The con-

tact 175 is located to engage a part of the flat surface 101, further indicated at 184 (Fig. 3) as a contacting portion of the upper fuse assembly fitting 100.

The location of the contacts 174, 175 on the cover is such that when the cover is closed and the fuse assembly is supported by the spring clip 78, as shown in Fig. 5, the contacts 174, 175 engage the contacts 73 and 184.

At its upper end the cover 26 is preferably provided with a heavy forwardly projecting lug or hinge arm 190, which preferably extends the full width of the cover and serves to support a pintle for the hinge.

This lug is provided with a transverse bore 191 for receiving the pintle 44, whereby the cover is pivotally supported at a point forward of the pivotal support of the fuse assembly.

The fused disconnect is preferably mounted at an angle, substantially the angle shown, which brings the pintle 44 of the cover and the trunnions 58 of the fuse assembly into about the same level, and enables me to bring about the cooperation between the lower ends of the fuse assembly and the cover involving the engagement of the keeper 157 with the shoulder 156 when the parts are in the position of Fig. 5, and their disengagement in the position of Fig. 6.

By providing the cover with a heavy pintle arm across its full width there is less danger of breakage of the cover across this arm, and greater resistance against abuse may be expected.

The circuit may then be traced as follows: One of the line conductors may come in at one of the apertures 68 of the housing, being engaged with the connector 61 (Fig. 5) in the bore 63, by screws 66. Current passes through the arm 71 to contact head 73, contact 174, pigtail 181, bridge 176, other pigtail 181, contact 175, contact surface 184 of the fuse fitting 100, fuse button 118, fuse 123, fuse pigtail 126, target head 34, contact 141, contact surface 93, pigtail 95, connector 88, to conductor in the bore 63, emerging from aperture 69 of the housing.

The operation of the fused disconnect is as follows: The arrangement of the fuse in the fuse unit has already been described, and when this is done, the parts of the fuse assembly will be in the position of Fig. 3. Assuming the fuse assembly is in the housing and the cover closed, and the fused disconnect switch is connected in the circuit, the device is now in the position of Fig. 5 and adapted to protect the circuit. Upon the passage of a current sufficient to rupture the fuse, the fuse will be ruptured and the explosive action of the gases will cause the ruptured fuse to be driven out of the lower end of the insulating tube 37.

The dangling end of the fuse, carried by the pigtail 126, is withdrawn from the end of the insulating tube 37 by plunger 132, actuated by the spring 133. Rupture of the fuse will thus permit the target 34 to move from the position of Fig. 5 to that of Fig. 10, where it will project from the lower end of the housing, and will indicate that the fuse is ruptured.

Thus it is not necessary to open the housing to ascertain whether the fuse is ruptured, but the lineman can see at once the condition of the fuse, without opening the housing.

Assuming that the fuse has been ruptured, it may be replaced as follows: A disconnect stick may have its head inserted in the aperture 163 of the cover. A pull exerted on the cover will be transmitted by the keeper 157 to the shoulder

156 of the fuse assembly. The fuse assembly and the cover will, therefore, pivot as one unit at the beginning of their motion away from the housing 25, and the cover will pull the fuse tube 37 out from between the legs of the spring clip 78.

After this amount of movement of the cover and fuse assembly together, the arrangement of the pivots of the fuse assembly at 58 and the cover at 44 is such that the keeper flange 172 moves out of engagement with the shoulder 156 of the fuse assembly, and the fuse assembly hangs free of the cover, as shown in Fig. 6. The cover may then be opened farther by means of the disconnect stick and may pivot upward to the dotted line position of Fig. 6, where it will rest backward against the stop surface 49, with the housing entirely open.

The disconnect stick may then have its head inserted in the slot 106 between the legs 103, 104 of the fuse assembly, and the fuse assembly may be lifted from its upper supports 59 by the disconnect stick. The fuse may be replaced and the fuse assembly then again replaced as a unit by means of a disconnect stick. In this replacement of the fuse assembly the trunnions 58 are again placed in the slot 57, the fuse assembly, with its fuse, hanging freely from its trunnions.

The cover may then be pivoted downward until the bridge 176 engages the face of the insulating tube 37 and forces the insulating tube to pivot with the cover. The insulating tube will then be forced in between the legs of the spring clip 83, where it will be retained to hold the cover and fuse assembly in the position of Fig. 5.

During this motion of the cover and fuse assembly the pivotal arrangement of the cover and fuse assembly is such that the keeper 157 has moved up behind the shoulder 156 on the fuse assembly, and the cover is again in position to pull out the fuse assembly, if the cover is opened.

As a general rule, it is not advisable to break the circuit by means of the mechanical contacts on such a fused disconnect, but such a break is nevertheless found necessary by linemen, and it can be effected very quickly by means of the present fused disconnect switch.

When the parts are in the position of Fig. 5 and the cover is opened, the circuit is broken at three places. It is broken below, between the contact surfaces 93 and 141, when the cover pulls the fuse assembly tube 37 out from between the legs of the spring clip 78. The circuit is also broken above at two points simultaneously, by disengagement of the contact 174 with the contact surface 73 and disengagement of contact 175 carried by the cover, with the contact surface 184.

When the switch is opened manually, the circuit is broken in three places, thus diminishing the tendency to arc. While a break at a contact located in a low part of the device might tend to cause the arc to spread to other parts, this is prevented by the additional two breaks that are produced at the top.

When the fuse is blown, there is a double break, the circuit being broken at the fuse in the tube and at the lower contact, when the target moves downward. This makes a much faster break of the circuit than anything in the prior art of which I am aware.

So far as I am aware, most of the prior art devices have the fuses attached to the cover, and they are not provided with any means for withdrawing the ruptured fuse from the tube.

The lower contact break avoids a high resist-

ance path which might occur through the carbonized inside of a tube. On a light overload a fuse may melt slowly, and the tube may burn slowly, thus carbonizing the inside.

In some embodiments of the invention the housing may be made of special glass, such as Pyrex, which would have the additional advantage that cracks in the glass become visible before any definite failure. A glass housing would have the additional advantage that internal conditions would be immediately visible, and insects, such as wasps, which might penetrate to the interior, would be visible from the outside. With a transparent housing, if an arc occurs at one spring, which might have failed, it would be immediately visible.

By reason of the mode of support of the cover, if the cover should be broken in two, the two upper contacts 174, 175 would be moved outward and would break the circuit through a double contact break, but it would not dislodge the fuse assembly. This condition would immediately become visible to the lineman by mere inspection from the ground.

Referring to Fig. 13, this is a fragmentary sectional view, showing the details of structure of the support of the bolts 11 and 12 in the housing member 25.

The housing member is provided with a pair of suitably located sockets 200, which taper inwardly for convenience in molding, and which are adapted to receive the heads 201 of the bolts. The head 201, having been located in the socket with the bolt in the desired position, the rest of the socket is filled in with cement 202 surrounding the head and engaging the walls of the socket and the shank of the bolt. This cement may be any suitable cementitious material adapted to have a good bond with the porcelain or the glass, and of an initially plastic, but finally rigid, form.

Referring to Figs. 14 and 15, these views show the details of structure of the threaded members, equivalent to a nut, by means of which the contacts, the keepers, clips, connectors, etc. may be secured to the porcelain housing.

In this case the porcelain housing again has a socket 200, and the threaded member, which is indicated by the numeral 81, may be a substantially cylindrical body, having the outwardly extending longitudinal ribs 203 and the annular ribs 204, 205.

The anchoring member 81 has a centrally located threaded bore 206, and at its outer end has a flat body flange 207, which may substantially cover the socket 200. At one end this body flange 207 has a slot 208, which provides an opening for the surplus cement to escape; or, if molten metal is used, provides a filling hole into which the metal may be inserted.

The body flange 207 preferably has a pair of outwardly projecting stop flanges 209, 210 which engage the opposite sides of the attachment flange 79 of the spring clip. Thus a single screw bolt 80 may serve to secure the spring clip to the anchoring member 81 without any possibility of turning of the clip on the anchoring member 81.

In this case the anchoring member 81 is again secured in the socket 200 by means of the cement 202, or the socket is filled about the anchoring member by pouring in molten metal, such as lead or solder, which engages the anchoring member and also engages the walls of the socket to anchor the member 81 in the socket.

This form of anchoring is contemplated in the present device with regard to the connector 88,

connector 61, supporting fixture 52, and keeper 157, and it may also be used for the anchoring of the contacts 174, 175 and bridge 176.

The anchoring devices referred to exemplify what is meant when it is stated that the metal part is secured by being embedded in the porcelain housing, as it is either embedded in soft metal or in cement, in a socket.

It will thus be observed that I have invented an improved fused disconnect, having many advantages over the prior art devices. When the fuse leader is thrown out of the present device, it is insulated, because contact has already been broken at the lower contact. When the switch is opened, there are multiple gaps produced, which tends to reduce arcing. When the fuse is ruptured, the door stays closed, as distinguished from the devices of the prior art, and the interior mechanism of this device is not exposed to the elements.

The present device is provided with a much stronger housing, and there is no danger that the device may be destroyed by breaking off the ears, which support the hinge. Such disconnect housings are subject to a great deal of abuse, as small boys sometimes throw rocks at them, and hunters shoot at them as targets.

In the present device the fuse unit may be removed by a switch stick, and it is not necessary to use the hands, as in the prior art devices. The plunger type of fuse withdrawing device is more compact than any of the devices of the prior art, and I believe that the double break in the fuse tube and at the lower contact, breaks the circuit considerably faster than in the prior art devices.

While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim as new and desire to secure by Letters Patent of the United States, is:

1. In a fused disconnect switch for high tension circuits, the combination of an insulating housing with a fuse unit mounted therein and connectors carried by said housing for establishing connection between a line and said fuse unit, said fuse unit including a fuse tensioned in an elongated insulating housing, and resilient means for withdrawing one end of said fuse on rupture of the fuse, said elongated housing comprising an insulating tube and a spring clip carried by said housing for engaging said insulating tube and retaining said fuse assembly in predetermined position.

2. A unitary fuse assembly comprising an insulating tube having connector means at one end for engagement with one end of a fuse in the tube and for connection to a circuit, and means for tensioning the fuse, comprising a spring pressed plunger carried by the other end of said tube and adapted to be secured to a leader from said fuse to urge said leader in such a direction that it will be withdrawn from the tube on rupture of the fuse, said spring pressed plunger being carried by another insulating tube, and a metallic fitting for securing said two tubes in substantially parallel relation.

3. In a fused disconnect switch, the combination of a housing with electrical connectors carried thereby for establishing an electrical connection to a fuse unit, a fuse unit adapted to be

removably carried by said housing and to be connected to said connectors, and a plurality of pairs of switch contacts arranged in series in said circuit and adapted to be broken when said fuse assembly unit is moved from the closed circuit position to the open circuit position.

4. In a fused disconnect switch, the combination of a housing with electrical connectors carried thereby for establishing an electrical connection to a fuse unit, a fuse unit adapted to be removably carried by said housing and to be connected to said connectors, and a plurality of pairs of switch contacts arranged in series in said circuit and adapted to be broken when said fuse assembly unit is moved from the closed circuit position to the open circuit position, and a movable cover carried by said housing, said cover being adapted to actuate said fuse assembly unit to open or close said contacts.

20 5. In a fused disconnect switch for high tension lines, an insulating housing comprising a main housing member constructed of ceramic materials and having an internal chamber for receiving a fuse assembly unit, a cover for closing said chamber, said main housing member having hinge ears for engaging a pintle pivotally supporting said cover, and a metal strap carried by said main housing member and having its ends also carrying said pintle whereby displacement of the housing by breakage of the pintle ears is prevented.

25 6. In a fused disconnect switch for high tension lines, an insulating housing comprising a main housing member constructed of ceramic materials and having an internal chamber for receiving a fuse assembly unit, a cover for closing said chamber, said main housing member having hinge ears for engaging a pintle pivotally supporting said cover, and a metal strap carried by said main housing member and having its ends also carrying said pintle whereby displacement of the housing by breakage of the pintle ears is prevented, said metal strap having predetermined of its parts secured to said main housing by location between opposing shoulders carried by said main housing.

30 7. In a fused disconnect switch, the combination of an insulating housing with a fuse assembly unit having a trunnion for pivotally supporting said unit, a bearing carried by said housing for engaging said trunnion, said fuse assembly unit comprising an insulating tube and a spring clip carried by said housing and engaging the sides of said insulating tube for holding said fused assembly unit in predetermined position in said housing.

35 8. In a fused disconnect switch, the combination of an insulating housing with a fuse assembly unit having a trunnion for pivotally supporting said unit, a bearing carried by said housing for engaging said trunnion, said fuse assembly unit comprising an insulating tube and a spring clip carried by said housing and engaging the sides of said insulating tube for holding said fused assembly unit in predetermined position in said housing, a cover pivotally mounted on said housing, and cooperating means between said cover and unit whereby the cover is held in closed position by said unit and spring clip.

40 9. In a fused disconnect switch, the combination of an insulating housing with a fuse assembly unit and means for securing said fuse assembly unit in said housing, switch contact means carried by a cover movably mounted in said housing and adapted to close the circuit

through said unit when said cover is closed, the breakage of said cover effecting an opening of the circuit.

10. In a fused cut-out, the combination of an insulating housing having a recess for receiving a replaceable fuse unit, with a replaceable fuse unit comprising an insulating tube having electrical connectors at its ends, and having a tensioned fuse extending between said connectors inside said tube, a cover pivotally mounted on said housing and adapted to effect a substantial closure of said recess, means for pivotally mounting one end of said fuse unit on said housing, and a resilient spring clip carried by said housing and adapted to engage said insulating tube to hold said fuse unit in operating position, said fuse unit in its operating position having one of its connectors engaging a contact carried by said housing and held in engagement by said spring clip engaging said insulating tube.

11. In a fused cut-out, the combination of an insulating housing having a recess for receiving a replaceable fuse unit, with a replaceable fuse unit comprising an insulating tube having electrical connectors at its ends, and having a tensioned fuse extending between said connectors inside said tube, a cover pivotally mounted on said housing and adapted to effect a substantial closure of said recess, means for pivotally mounting one end of said fuse unit on said housing, and a resilient spring clip carried by said housing and adapted to engage said insulating tube to hold said fuse unit in operating position, said fuse unit in its operating position having one of its connectors engaging a contact carried by said housing and held in engagement by said spring clip engaging said insulating tube, said contact being carried by a connector on said housing, and an electrically conducting flexible conductor extending from said connector to said contact at a point adjacent the contacting portion of said contact, whereby the contact is adapted to retain its resiliency due to the lack of heating current in the contact.

12. In a fused cut-out, the combination of a fuse unit comprising an insulating tube having electrical connectors adjacent its opposite ends, and having a tensioned fuse in said tube between said connectors, with a housing member adapted to support said fuse unit, said housing member having a connector carried thereby, and a resilient spring contact carried by said connector, said contact engaging one of the connectors on said fuse unit, and a flexible lead connected to the connector carried by said housing and to the contacting portion of said resilient contact, whereby the major portion of the current is carried by said lead, and the heating of the contact and resultant loss of its resiliency is substantially eliminated.

13. In a fused cut-out, the combination of an insulating housing with a fuse unit, said fuse unit comprising an insulating tube having electrical unit connectors located adjacent its ends, and having a tensioned fuse in said tube connecting said unit connectors, means for securing said fuse unit in said housing, an electrical connector carried by said housing for engaging one of the unit connectors, and a second electrical connector carried by said housing adjacent the other of said unit connectors, a cover movably mounted on said housing and having a bridging contact, said bridging contact engaging the lat-

ter of said connectors on said housing and engaging the other of said unit connectors, and means connecting said cover and fuse unit, whereby an opening movement of the cover effects a triple break of the circuit, including all of said connectors and fuse unit and bridging contacts.

14. In a fused cut-out, the combination of an insulating housing with a fuse unit, said fuse unit comprising an insulating tube having electrical unit connectors located adjacent its ends, and having a tensioned fuse in said tube connecting said unit connectors, means for securing said fuse unit in said housing, an electrical connector carried by said housing for engaging one of the unit connectors, and a second electrical connector carried by said housing adjacent the other of said unit connectors, a cover movably mounted on said housing and having a bridging contact, said bridging contact engaging the latter of said connectors on said housing and engaging the other of said unit connectors, and means connecting said cover and fuse unit, whereby an opening movement of the cover effects a triple break of the circuit, including all of said connectors and fuse unit and bridging contacts, said cover being constructed and arranged for pivotal movement on said housing in such manner as to effect a double break of the circuit at said bridging contact at the upper part of said cut-out first, to avoid the upward travel of an arc from the other break in said circuit.

15. In a fused cut-out, the combination of an insulating housing with a fuse unit comprising an insulating tube, a pair of connectors carried by said tube, and a tensioned fuse in said tube connecting said connectors with connector means carried by the housing for engaging the connectors of said fuse unit, means for pivotally mounting said fuse unit at the upper part of said housing, a cover for said housing, and means for pivotally mounting it on said housing, and latching means operating between said fuse unit and said cover to hold the cover closed when the fuse unit is in its operative position, said latching means automatically becoming disengaged after a predetermined pivotal movement of the fuse unit and cover, by virtue of the location of the points of pivotal support of the fuse unit and the cover.

16. In a housing for fused cut-outs, the combination of an insulating housing of a frangible nature, said housing being formed with an end wall, a rear wall, and a pair of forwardly projecting side walls, and having a fuse unit recess therein, with a cover of insulating material, and a pintle for mounting said cover for pivotal movement on the side walls of said housing, and metal reinforcing means carried by said housing and embracing the rear wall and the side walls thereof, and extending into engagement with said pintle whereby the breakage of the side walls adjacent said pintle is substantially eliminated.

17. In a fuse unit for fused cut-outs, the combination of an insulating tube with a tubular metallic connector carried by each end of said tube, one of said tube ends being open for passage of a fuse, said fuse unit having its connector adjacent said open end provided with a bore having its axis extending substantially parallel to said insulating tube, a second insulating tube located in said bore, a spring pressed plunger located in said second insulat-

ing tube, and a laterally projecting arm carried by said plunger and adapted to serve as a contact for engaging a housing contact.

18. In a fused cut-out, the combination of an insulating housing with a fuse unit comprising an insulating tube, connectors carried by said tube, and a fuse tensioned in said tube between said connectors, said housing having a recess for said unit, a connector carried by said hous-

ing adjacent the upper end of said fuse unit, a cover pivotally mounted on said housing and having a bridging contact for engaging said latter connector and the adjacent connector on said fuse unit, and means for securing the opposite end of said cover to said housing, said bridging contact opening the circuit when the cover is broken.

DAVID C. HUBBARD.
